(57) **CLAIM**

The ornamental design for an accessory clip, as shown and described.

DESCRIPTION

FIG. 1 is a perspective view from the front, top, and left side of the accessory clip;

FIG. 2 is a front elevation view of the accessory clip of FIG. 1;

FIG. 3 is a right side elevation view of the accessory clip of FIG. 1;

FIG. 4 is a left side elevation view of the accessory clip of FIG. 1;

FIG. 5 is a top plan view of the accessory clip of FIG. 1;

FIG. 6 is a bottom plan view of the accessory clip of FIG. 1;

FIG. 7 is a rear elevation view of the accessory clip of FIG. 1;

FIG. 8 is an exploded perspective view from the front, top, and left side of the accessory clip of FIG. 1;

FIG. 9 is a perspective view from the front, top, and left side of the plate part of the accessory clip of FIG. 1, shown separately for ease of disclosure;

FIG. 10 is a front elevation view of the plate part of the accessory clip of FIG. 9, shown separately for ease of disclosure;

FIG. 11 is a right side elevation view of the plate part of the accessory clip of FIG. 9, shown separately for ease of disclosure;

FIG. 12 is a left side elevation view of the plate part of the accessory clip of FIG. 9, shown separately for ease of disclosure;

FIG. 13 is a top plan view of the plate part of the accessory clip of FIG. 9, shown separately for ease of disclosure;

FIG. 14 is a bottom plan view of the plate part of the accessory clip of FIG. 9, shown separately for ease of disclosure;

FIG. 15 is a rear elevation view of the plate part of the accessory clip of FIG. 9, shown separately for ease of disclosure;

FIG. 16 is a perspective view from the front, top, and left side of the flange part of the accessory clip of FIG. 1, shown separately for ease of disclosure;

FIG. 17 is a perspective view from the rear, top, and left side of the flange part of the accessory clip of FIG. 16, shown separately for ease of disclosure;

FIG. 18 is a front elevation view of the flange part of the accessory clip of FIG. 16, shown separately for ease of disclosure;

FIG. 19 is a right side elevation view of the flange part of the accessory clip of FIG. 16, shown separately for ease of disclosure;

FIG. 20 is a left side elevation view of the flange part of the accessory clip of FIG. 16, shown separately for ease of disclosure;

FIG. 21 is a top plan view of the flange part of the accessory clip of FIG. 16, shown separately for ease of disclosure;

FIG. 22 is a bottom plan view of the flange part of the accessory clip of FIG. 16, shown separately for ease of disclosure; and,

FIG. 23 is a rear elevation view of the flange part of the accessory clip of FIG. 16, shown separately for ease of disclosure.

The broken lines depict portions of the article that form no part of the claimed design.
